VIBRATION RESPONSIVE MECHANISM FOR A DOMESTIC APPLIANCE

Edward J. Frey, Dayton, Ohio, assignor to General Motors Corporation, Detroit, Mich., a corporation of Delaware

Filed Mar. 26, 1957, Ser. No. 648,580

11 Claims. (Cl. 68—24)

This invention relates to a domestic appliance and more particularly to control apparatus for laundry machines.

An object of the invention is to provide control mechanism for controlling the speed of rotation of a tumbling drum of a washing machine or combined washer-dryer so as to prevent dangerous vibration of the machine when the drum contains an unbalanced load.

Another object of this invention is to provide a laundry machine including a rotatable clothes container with drive means for rotatably spinning the container at high speed, the high speed spinning of the container being terminated upon excessive axial vibratory movement of the clothes container and upon excessive transverse vibratory movement of the clothes container.

Still another object of this invention is to provide control mechanism for controlling the high speed spinning of the tumbling drum of a laundry machine, the control mechanism being responsive to unbalanced vibratory movement of the drum and wherein the sensitivity of the control mechanism is regulated as a function of the load carried by the drum.

Still another object is to provide laundry apparatus including a tub and a rotatable tumbling drum therein with control mechanism for controlling high speed spinning of the drum, the control mechanism preventing high speed spinning of the drum when the tub is carrying an excessive load.

Another object of this invention is to provide a laundry machine of the type having a horizontally arranged tub and a horizontally arranged tumbling drum therein with a clothes deflector that is secured to the tub and which extends into the tumbling drum to deflect clothes toward the middle of the tub in order to prevent unbalanced loads from occurring in the tumbling drum and tub.

Further objects and advantages of the present invention will be apparent from the following description, reference being had to the accompanying drawings, wherein a preferred form of the present invention is clearly shown.

In the drawings:

Figure 1 is a side view, with parts broken away, of the laundry apparatus of this invention showing the location of the control mechanism for controlling the spinning of the tumbling drum of the machine;

Figure 2 is a circuit diagram illustrating the control circuit for controlling the electric motor and two-speed transmission that drives the tumbling drum of the laundry machine;

Figure 3 is an enlarged vertical sectional view of the bump switch mechanism shown in Fig. 1 and taken along line 3—3 of Figure 4;

Figure 4 is a plan view taken along line 4—4 of Figure 3;

Figure 5 is a top plan view taken along line 5—5 of Figure 3;

Figure 6 is an enlarged front plan view of the clothes deflector shown in Figure 1; and

2

Figure 7 is an enlarged top plan view of the clothes deflector shown in Figure 1.

Referring now to the drawings and more particularly to Fig. 1, a laundry machine is shown and is generally designated by reference numeral 10. The laundry machine is illustrated as a clothes washer although the control mechanism for driving the tumbling drum of the laundry machine might equally well be used with combined washer-dryers. The clothes washer comprises a main frame 12 which supports a rear panel 14, a top panel 16 and front panels 18. A removable decorative front panel 22 covers the front panels 18. A cylindrically shaped horizontally arranged tub 24 is supported from the frame 12 by means of springs 26 and shock absorbers 28 that are interposed between the frame and tub. The springs and shock absorbers are pivoted to the frame and to the tub 24. The shock absorbers and springs are located at opposite sides of the tub and approximately midway the horizontal length of the tub. The shock absorber and spring on the righthand side of tub 24 as viewed from the front is not shown in Fig. 1 but it is identical with the shock absorber and spring on the lefthand side, which is shown in Fig. 1. A torsion bar 30 is pivoted in suitable bearings to the main frame 12 and to the tub 24 to substantially prevent front-to-back movement of the tub 24. The springs 26 and shock absorbers 28 serve to prevent transverse or side-to-side motion of the tub 24. This suspension arrangement for the tub 24 is described in greater detail in copending applications Ser. No. 623,052, filed November 19, 1956, and Ser. No. 547,475, filed November 17, 1955, now abandoned.

A tumbling drum 32 having a perforate peripheral wall and formed with the usual tumbling vanes 34 is disposed within the tub 24. The tumbling drum 32 is fixed to a shaft 36 that is journaled within a bearing 38 fixed to the rear wall of tub 24. The tumbling drum has a conically shaped rear wall portion 40, as illustrated in Fig. 1. The tumbling drum 32 has a front access opening 42 that is in alignment with front access openings formed in the tub 24 and in front cabinet wall 18. A tubular flexible member 44 made of rubber or the like is interposed between the tub 24 and the front wall 18 of the clothes washer. A door 46 is pivoted to the decorative panel 22 of the washer and abuts a peripheral edge of the flexible tubular member 44 when in a closed position.

The tumbling drum 32 is driven by an electric motor 48 which is secured to tub 24. The electric motor is drivably connected to any well-known solenoid operated two-speed transmission mechanism designated by reference numeral 48. The output shaft of the transmission mechanism is connected with a pulley 50 which drives a pulley 52 by means of a suitable V-belt 54. The pulley 52 is connected with shaft 36 so that rotation of pulley 52 rotates the tumbling drum 32. The two-speed transmission mechanism 48 is ordinarily in a low speed position and is shifted to a high speed position whenever solenoid 56 is energized. The clothes washer is provided with suitable water inlet means (not shown) which may be of the type disclosed in copending application Ser. No. 623,052, filed November 19, 1956. The water inlet apparatus is controlled by a conventional timer 58 having the usual timer operated switches. The electric motor 48 also drives a pump 60 which operates to exhaust water from the tub 24 during certain portions of the washing cycle.

The washing machine is provided with control mechanism for controlling the spinning speed of tumbling drum 32. To this end a time delay switch 62 of any well-known construction is attached to front wall 18 of the wash-

ing machine adjacent the upper left-hand corner thereof. The time delay of the switch operates to delay closure of the switch for a predetermined period of time once the switch is moved to an open position. A switch actuator designated as a whole by reference numeral 64 is attached to the tub 24 and is in general alignment with a button 66 that operates the switch 62. As is more fully described hereinafter, the switch 62 will be moved to an open position by switch actuator 64 whenever the tub 24 vibrates excessively in a front-to-back motion or in a transverse side-to-side motion and whenever the tub 24 is overloaded.

The energizing circuit for tumbling drum driving motor 46 and solenoid 56 is illustrated in Fig. 2. As shown in this figure, the motor 46 is connected in series with a timer operated switch 58a and in series with input lines L₁ and L₂ which are connected with a suitable voltage source. The solenoid 56 is connected in series with timer operated switch 58b and with out-of-balance switch 62. During the washing cycle of the washing machine the tumbling drum is driven at low tumbling speed by motor 46 whenever timer operated switch 58a is closed. During a spin-dry period of operation of the washer when the tumbling drum 32 is rotated at a higher speed to extract moisture from the clothes contained therein, the timer operated switch 58b is closed as well as timer operated switch 58a. The two-speed transmission 48 will not shift to high speed operation unless switch 62 is closed and switch 62 is normally closed except under certain conditions to be described hereinafter.

The switch actuating mechanism generally designated by reference numeral 64 in Fig. 1 is disclosed in greater detail in Figs. 3, 4 and 5. The actuating mechanism includes a bracket 67 that is bolted to tub 24. A plate member 68 is pivotally secured to bracket 67 by means of screws 70, the top screw passing through a slot 72 formed in plate 68 whereby the plate may be pivotally adjusted with respect to bracket 67. A switch actuating plate 74 is riveted or otherwise secured to plate 68. This plate may be adjusted relative to switch actuating button 66 by the adjustment of screw mechanism 75. The plate 74 has a substantially horizontally extending face 76, a vertically extending switch actuating face 78, and a third actuating face 80 that is inclined to the horizontal. The switch actuating faces 76, 78 and 80 are all adapted to contact switch actuating knob 66 which, when moved rightwardly in Figs. 3 and 5, opens the switch 62 for a predetermined period of time depending upon the time delay of the switch. It can be seen from Figs. 3, 4 and 5 that switch actuating face 80 will trip open switch 62 whenever the tub 24 is moved transversely of the cabinet. This transverse or side-to-side motion is partially along an arcuate path due to the fact that the tub is pivotally connected to torsion bar 30. This motion occurs when the clothes are unevenly distributed around the circumference of the tumbling drum 32. Thus, when solenoid 56 is energized to go into high speed spinning and assuming an uneven clothes distribution, a sudden torque force is set up to move tub 24 sideways, a distance sufficient to trip switch 62. The switch actuating face 78 will contact switch actuating button 66 whenever tub 24 is moved front-to-back by an excessive vibratory movement. The switch actuating face 76 will contact the switch button 66 to open switch 62 whenever the tub 24 moves downwardly with respect to frame 12. Thus, when the tub 24 is filled with water to some predetermined level, the switch actuating face 76 will contact switch button 66 to hold the switch 62 in an open position.

Since the tub 24 is resiliently supported by springs 26, the tub 24 will move closer and closer to frame 12 as the load of clothes in the tumbling drum 32 is increased. Moreover, since cam face 80 is inclined to the vertical as illustrated in Fig. 4, the cam face will move closer to switch actuating button 66 as the load in tumbling drum 32 and tub 24 is increased. The distance between switch-

actuating button 66 and cam face 80 is thus related to the amount of load contained in tumbling drum 32, the cam face 80 being closer to button 66 as the load is increased. It will be obvious that less out-of-balance transverse movement of tub 24 is necessary to trip switch 62 when the tumbling drum 32 is heavily loaded as compared to the condition when the tumbling drum is lightly loaded. The sensitivity of operation of switch 62 thus varies as a function of the load in tumbling drum 32.

As noted hereinbefore, the torsion bar 30 prevents substantially all front-to-back motion of tub 24. The possibility of unbalanced front-to-back motion of tub 24 is further reduced by the provision of a clothes deflector generally designated by reference numeral 82 that is attached to the inner wall of tub 24 and which extends into tumbling drum 32. This clothes deflector is made of metal or other suitable material and has a relatively narrow portion 82a that merges into a relatively wide portion 82b as more particularly illustrated in Figs. 6 and 7. The clothes deflector deflects clothes toward a point located midway the length of tumbling drum 32, which coincides substantially with the point of attachment of the springs 26 and shock absorbers 28 to the tub 24. During rotation of tub 32 the clothes move upwardly along face 82a of the clothes deflector and then slide off the deflector toward the midpoint of tumbling drum 32. The conically shaped rear wall 40 of the tumbling drum also tends to deflect the clothes to a point overlying springs 26 and shock absorbers 28. The deflector 82 and conically shaped rear wall 40 thus both tend to center the load of clothes over the springs 26 and shock absorbers 28 to provide for a balanced clothes load in tumbling drum 32. With the clothes load centered over springs 26 and shock absorbers 28, the possibility of excessive front-to-back vibration of tumbling drum 32 and tub 24 is reduced.

The operation of the clothes washer and control mechanism therefor will now be briefly described. An operator desiring to use the clothes washer places the clothes within tumbling drum 32 and sets the timer 58 into operation. The timer operates suitable water filling mechanism to fill the tub 24 to a predetermined level, as is well known to those skilled in the art. The tumbling drum 32 is then slowly rotated for agitation of the clothing, the solenoid 56 being deenergized at this time whereby the two-speed transmission 48 is in its low speed position. After the washing cycle has been completed, the tub 24 is drained of wash water by pump 60, the wash water being conducted to a suitable drain. When the water has been exhausted from tub 24 the timer actuated switch 58b is closed to complete a circuit to solenoid 56. The solenoid 56 shifts the transmission 48 to its high speed position wherein the tumbling drum 32 is rotated at a high spinning speed for extracting moisture from the clothes contained therein. If there is an unbalanced load in tumbling drum 32, that is, where the clothes are unevenly distributed around the periphery of the tumbling drum, the switch 62 will be opened to open a circuit to solenoid 56 whereupon the tumbling drum 60 continues to be rotated, but at a low speed. The switch 62 is generally tripped shortly after the solenoid 56 is energized due to the fact that an unbalanced load at this time creates a sudden transverse or side-to-side movement of tub 24, whereupon cam face 80 trips switch 62.

In the event that the tub 24 is not exhausted of wash water prior to the spinning operation, the tub will move down toward frame 12 and the switch actuating face 76 of actuator 64 will hold the switch 62 in an open position. Thus, the drum 32 can never be spun at high speed when the tub 24 is filled with water to some predetermined level.

If the tub 32 contains an unbalanced clothes load front-to-back, that is, where clothes are piled up near the front or rear wall of the drum 32, the tub 24 may vi-

biate front-to-back whereupon switch actuating face 78 of actuator 64 will open switch 62.

It should be noted, however, that when switch 58b is closed to provide for the spin cycle of the washing machine and wherein switch 62 has been opened by an excessive vibratory movement of tub 24, the tumbling drum still continues to rotate at low speed since the transmission 48 automatically cuts back to its low speed position whenever solenoid 56 is deenergized. The tumbling drum 32 will thus be rotated at slow speed for a period determined by the time delay of switch 62, and during this period the clothes normally will redistribute themselves so that upon subsequent closure of switch 62, high speed spinning will take place without tripping switch 62. In other words, the time delay of switch 62 provides a period of time wherein the tumbling drum is rotated at low speed to remedy the unbalanced clothes load condition.

While the form of embodiment of the invention as herein disclosed constitutes a preferred form, it is to be understood that other forms might be adopted, as may come within the scope of the claims which follow.

What is claimed is as follows:

1. Laundry apparatus comprising, a rotatable clothes container, drive means for said container including means for driving said container at a low speed and at a higher speed, control means responsive to excessive vibration of said container for preventing operation of said container at high speed while permitting low speed operation, and means for automatically varying the sensitivity of said control means as a function of load in the clothes container.

2. Laundry apparatus comprising, a tub, a rotatable clothes container in said tub, drive means for said clothes container including a two speed transmission for driving said container at low and high speeds, control means for shifting said transmission from low to high speed operation, and means responsive to a predetermined loading of said tub for automatically varying the point at which said transmission is shifted to high speed operation.

3. A laundry machine comprising, a tub, a substantially horizontally arranged rotatable clothes container in said tub, drive means for said container including two speed transmission means for driving said container at low and high speeds, electrically operable means for shifting said transmission means from low to high speed operation, an energizing circuit for said electrically operable means, a switch connected in series with said energizing circuit and said electrically operable means, and means for moving said switch to an open position in response to a predetermined loading of said tub, excessive side to side vibration of said container, and excessive front to back vibration of said container along the axis of rotation of said container.

4. A laundry machine comprising, a cabinet, a tub in said cabinet, a rotatable clothes container in said tub, said tub and container being resiliently supported from said cabinet, drive means for said container including two speed transmission means for driving said container at a low and at a higher speed, a solenoid for shifting said transmission means to high speed operation when energized, an energizing circuit for said solenoid, an electrical switch connected in series with said solenoid and said energizing circuit, said switch being fixed with respect to said cabinet and including an actuating member, and a switch actuator including a non-vertically inclined actuating face mounted for movement with said tub, said actuating face operating to open said switch upon excessive vibratory movement of said tub, the distance between said inclined actuating face and said switch actuating member varying as a function of the load in said container.

5. A laundry machine comprising, a rotatable clothes container, drive means for said container including means

for driving said container at high spinning speed, control means responsive to excessive vibratory movement of said container for terminating high speed operation of said container, and means for automatically varying the sensitivity of said control means as a function of load in the clothes container.

6. A clothes washer comprising, a cabinet, a substantially horizontally arranged tub in said cabinet, a tumbling drum supported for rotation in said tub, resilient means for supporting said tub from said cabinet, drive means including two speed transmission means for driving said tumbling drum at a low tumbling speed and at a high extracting speed, a solenoid for shifting said transmission means to high speed operation when energized, an energizing circuit for said solenoid, a switch connected in series with said solenoid and energizing circuit, and a switch actuator secured to said tub, said actuator having a substantially vertically extending face and a second face located at an angle thereto, said vertically extending face operating to open said switch upon excessive front to back vibratory movement of said tub and said second face operating to open said switch upon excessive side to side vibratory movement of said tub.

7. A laundry machine comprising, a horizontally arranged tub, a frame member, resilient means for supporting said tub from said frame member and connected to said tub substantially midway the length thereof, a tumbling drum supported for rotation in said tub, and a clothes deflector secured to said tub and extending into said tumbling drum, said clothes deflector having a narrow portion for receiving said clothes and a relatively wide portion for deflecting clothes toward the area overlying the point of connection of said resilient means with said tub when said tub is rotating.

8. A laundry machine comprising, a horizontally arranged tub, a frame member, resilient means for supporting said tub from said frame member and connected to said tub substantially midway the length thereof, a tumbling drum supported for rotation in said tub, drive means for said tumbling drum including two speed transmission mechanism for driving said tumbling drum at a low speed and at a higher speed, a solenoid for shifting said transmission to its high speed setting, an energizing circuit for said solenoid including a switch movable to an open position in response to excessive front to back motion of said tub along the axis of rotation of said tumbling drum, and a clothes deflector secured to said tub and extending into said tumbling drum for deflecting clothes toward a point located midway the length of the tumbling drum to minimize said front-to-back motion.

9. A clothes washer comprising, a cabinet, a horizontally arranged tub in said cabinet, a tumbling drum supported for rotation in said tub, resilient means for supporting said tub, an electric motor for driving said tumbling drum, two speed transmission means connected between said electric motor and said drum for driving said drum at a low speed and at a higher speed, a solenoid for shifting said transmission means to high speed operation, an energizing circuit for said solenoid including a switch connected in series therewith, said switch being fixed to said cabinet and having a switch actuator extending outwardly therefrom, and a switch tripping member secured to said tub in a position adjacent said switch actuator, said tub and tripping member moving downwardly on said resilient means to a point where said tripping member contacts said switch actuator to open said switch when said tub is carrying a predetermined load of water, whereby said tub is prevented from operating at said higher speed when said tub contains said predetermined water load.

10. A clothes washer comprising, a frame, a cabinet, a horizontally arranged tub in said cabinet, a tumbling drum supported for rotation in said tub, resilient means for supporting said tub from said frame, a torsion bar extending lengthwise of said tub and pivotally connected

to said tub and frame, an electric motor for driving said tumbling drum, two speed transmission means connected between said electric motor and said drum for driving said drum at a low speed and at a higher speed, a solenoid for shifting said transmission means to high speed operation, an energizing circuit for said solenoid including a time delay switch connected in series therewith, said switch being fixed to said cabinet and having a switch actuator extending outwardly therefrom, and a switch tripping member secured to said tub in a position adjacent said switch actuator, said tripping member contacting said switch actuator to open said switch upon excessive front to back vibration of said tub along the axis of rotation of said drum, upon excessive side to side vibration of said tub, and when said tub carries a predetermined load.

11. A vibration control for apparatus having a rotating member and a stationary support member for said rotating member comprising a switch portion on one of said members, a switch actuator for said switch, and a

10

15

20

switch tripping portion on the other of said members adjacent said actuator, said tripping portion contacting said actuator to open said switch upon excessive vibration of said rotating member along the axis of rotation of said rotating member, upon excessive vibration of said rotating member in a direction other than along said axis, and when said rotating member carries a predetermined load.
